UNITED STATES PATENT OFFICE.

MURIEL V. NOYES, OF BOSTON, MASSACHUSETTS.

SAND TOY.

1,210,354.

Specification of Letters Patent. Patented Dec. 26, 1916.

Application filed April 6, 1916. Serial No. 89,478.

To all whom it may concern:

Be it known that I, MURIEL V. NOYES, a citizen of the United States, residing at Boston, in the county of Suffolk and State of 5 Massachusetts, have invented an Improvement in Sand Toys, of which the following is a specification.

Children delight in playing with moist sand, as beach sand, for instance, and, with 10 their hands and crude utensils, build forms which simulate various objects.

This invention has for its object the provision of a device with which moist sand may be associated by which to simulate distinctive objects such as trees, shrubs, etc., although effective results may be obtained by the employment of dry sand, and also by the employment of both moist and dry sand.

The device consists essentially of a stem, 20 the lower end-portion of which is adapted to be thrust down into the sand, or to be embedded therein, and one or more supporting-plates arranged thereon and adapted to be supported thereby in elevated position, the 25 said plate or plates being adapted to receive and support a quantity of moist or dry sand, or both, which is usually arranged thereon in an irregular manner, thereby to simulate a tree or shrub. The plate or plates may be 30 made of different designs, and of different sizes, and may be resilient. To insure stability, in case it is desired to elevate the supporting-plate or plates well above the level of the sand, one or more base-plates may be 35 attached to the lower end of the stem which are adapted to be embedded in sand.

Another object of the invention is the provision of one or more base-plates of dimensions which differ from the supporting- 40 plates, and which may be of any desired shape, thus adapting them to serve as supporting-plates, when the device is reversed, in position, so that distinctive objects of different dimensions or other distinctive objects may be simulated.

Figure 1 is a side elevation of a device 45 with which sand may be associated to simulate distinctive objects such as trees, shrubs, etc. Fig. 2 is a plan view of the device of 50 Fig. 1. Figs. 3 and 4 are side and plan views of a modification to be referred to. Figs.

5 and 6 are side and plan views of another modification. Fig. 7 is a view of the device of Fig. 5, with sand thereon. Fig. 8 is a side elevation of another modification. Fig. 55 9 is a side view of the device of Fig. 5, reversed. Fig. 10 is a plan view of a modified form of supporting-plate. Fig. 11 is a side view of the form shown in Fig. 6, having sand arranged on its supporting-plate. 60

10 represents the stem, which consists of a small or slender piece of wood, wire or other material, and 12 and 13 are supporting-plates arranged thereon in any suitable manner at or near one end, and spaced apart. 65 They are preferably arranged in horizontal planes, and may be fixed or rotatably mounted on the stem, a short distance remote from its end, leaving a projecting end-portion. They may be made of different dimensions, and designs, and also may be resilient. The stem 10 is adapted to be arranged in upright position in the sand, and moist or dry sand, or a mixture of these, will be arranged upon the supporting-plates 70 12 and 13, the sand being piled thereon more or less loosely. In case a single supporting-plate is employed, which is of circular formation, see Figs. 5, 6, and 7, a bay tree or similar distinctive object may be simulated; 75 12 and 13, the sand being piled thereon more or less loosely. In case a single supporting-plate is employed, which is of circular formation, see Figs. 5, 6, and 7, a bay tree or similar distinctive object may be simulated; 80 or in case the supporting-plate is of irregular shape, comprising numerous arms, as 20, extended in various directions from the stem, see Fig. 10, another kind of tree or shrub will be simulated; in case two supporting-plates are employed, see Figs. 1 to 85 4, one may be made of larger dimensions than the other; in case the plate or plates are rotatably mounted on the stem, and comprising arms extended in various directions, 90 they may be turned relatively to one another, to thus vary the shape of the distinctive object which will be formed. It is an advantage to have the end of the stem project a short distance above the supporting-plate 95 or plates, to assist in holding the pile of moist sand in place.

15 and 16 represent base-plates which may be arranged on the stem in a manner similar to the supporting-plates, and when said 100 base-plate or plates are embedded in the sand, the stability of the device will be in-

creased. Said base-plates may, like the supporting-plates, be made of different dimensions and of various designs. If desired, the device may be reversed in position, see 5 Fig. 9, and distinctive objects of different dimensions, or other distinctive objects may be simulated. The base-plates, like the supporting-plates, are preferably attached to the stem a short distance remote from its 10 end, and for the same reason. When the device is reversed, the supporting-plate or plates 12 and 13 will be embedded in the sand.

I claim:

- 15 1. A device for simulating distinctive objects of sand, comprising a stem and one or more supporting-plates arranged thereon, said plates adapted to receive upon them the sand.
- 20 2. A device for simulating distinctive objects of sand, comprising a stem and one or more supporting-plates arranged thereon at approximately right angles thereto, said plates adapted to receive upon them the sand.
- 25 3. A device for simulating distinctive objects of sand, comprising a stem and one or more supporting-plates rotatably arranged thereon, said plates adapted to receive upon them the sand.
- 30 4. A device for simulating distinctive objects of sand, comprising a stem and one or more supporting-plates arranged thereon, having arms extended in various directions, said plates adapted to receive upon them the sand.
- 35 5. A device for simulating distinctive objects of sand, comprising a stem and one or more resilient supporting-plates arranged thereon, said plates adapted to receive upon them the sand.
- 40 6. A device for simulating distinctive objects of sand, comprising a stem and one or more supporting-plates arranged thereon having resilient arms extended in various directions, said plates adapted to receive upon them the sand.
- 45 7. A device for simulating distinctive objects of sand, comprising a stem and one or more supporting-plates rotatably arranged thereon having resilient arms extended in various directions, said plates adapted to receive upon them the sand.
- 50 8. A device for simulating distinctive objects of sand, comprising a stem and one or more supporting-plates arranged thereon, remote from the end, said plates adapted to receive upon them the sand.
- 55 9. A device for simulating distinctive objects of sand, comprising a stem and a plurality of supporting-plates of different dimensions arranged thereon and spaced apart.
- 60 10. A device for simulating distinctive objects of sand, comprising one or more sup-

porting-plates, and means for holding said 65 plates in elevated position, said plates adapted to receive upon them the sand.

11. A device for simulating distinctive objects of sand, comprising a stem, one or more supporting-plates arranged thereon at 70 one end, and one or more base-plates arranged thereon at the other end.

12. A device for simulating distinctive objects of sand, comprising a stem, one or more supporting-plates arranged thereon at one 75 end, and one or more base-plates arranged thereon at the other end, the base-plates being disposed at approximately right angles to the stem.

13. A device for simulating distinctive objects of sand, comprising a stem, one or more supporting-plates arranged thereon at one end, and one or more base-plates rotatably mounted thereon at the other end.

14. A device for simulating distinctive objects of sand, comprising a stem, one or more supporting-plates arranged thereon at one end, and one or more base-plates arranged thereon at the other end, the base-plates having 85 arms extended in various directions.

15. A device for simulating distinctive objects of sand, comprising a stem, one or more supporting-plates arranged thereon at one end, and one or more resilient base-plates arranged thereon at the other end.

16. A device for simulating distinctive objects of sand, comprising a stem, one or more supporting-plates arranged thereon at one end, and one or more base-plates mounted thereon, having resilient arms extended in 100 various directions.

17. A device for simulating distinctive objects of sand, comprising a stem, one or more supporting-plates arranged thereon, and a plurality of base-plates rotatably mounted 105 thereon having resilient arms extended in various directions.

18. A device for simulating distinctive objects of sand, comprising a stem, one or more supporting-plates arranged thereon at one 110 end, and one or more base-plates arranged thereon remote from the other end.

19. A device for simulating distinctive objects of sand, comprising a stem, one or more supporting-plates arranged thereon, and 115 one or more base-plates arranged thereon, the said base-plates being of different dimensions and spaced apart.

20. A device for simulating distinctive objects of sand, comprising one or more supporting-plates, and one or more base-plates, and means for supporting them with one set of plates adapted to be embedded in the sand, and the other set of plates to be held in elevated position.

21. A device for simulating distinctive objects of sand, comprising a main support having sand supporting elements arranged

thereon to receive upon them and support the sand, and to give contour to the object.

22. A device for simulating distinctive objects of sand, comprising a main support having elements extended therefrom arranged to receive upon them and support the sand, and to give contour to the object.

In testimony whereof, I have signed my name to this specification in the presence of two subscribing witnesses.
